WINDING APPARATUS

Ed Fletcher, Newark, Ohio, assignor to Owens-Corning Fiberglas Corporation, a corporation of Delaware

Application June 13, 1942, Serial No. 446,988

5 Claims. (Cl. 242—43)

This invention relates to winding apparatus for packaging material in strand form and refers more particularly to improved means for winding a continuous strand of material on a revolvable supporting member. It has special applicability to high speed winding as in the formation and concurrent packaging of strands of fibers such as glass, resin, and the like.

One of the principal objects of this invention is to build up a continuous strand of material on a revolvable supporting member by winding the strand around the supporting member in a manner to form a plurality of superposed rows of adjacent turns of the strand which are centered with respect to one another in the direction of the axis of the supporting member and which progressively decrease in length from the inner row to the outer row. As a result of the above arrangement, the opposite end walls of the package taper or slope toward each other sufficiently to enable extremely high speed rotation of the supporting member without the danger of the end turns sliding off the adjacent turns and becoming tangled or snarled. This is advantageous not only because it facilitates manufacture in permitting a larger package to be built up but also because it prevents the formation of ringers during subsequent unwinding of the package.

A further object of this invention is to accomplish the foregoing with apparatus which is simple in construction and thoroughly automatic in operation.

The foregoing, as well as other objects, will be made more apparent as this description proceeds, especially when considered in connection with the accompanying drawings, wherein:

Figure 1 is a diagrammatic elevational view of apparatus embodying my improved traversing means;

Figure 2 is a plan view of a portion of the apparatus shown in Figure 1;

Figure 3 is a vertical sectional view of the apparatus shown in Figure 2 taken on the line 3—3 of Figure 2;

Figure 4 is a vertical sectional view taken on the line 4—4 of Figure 2;

Figure 5 is a sectional view taken in the plane of the line 5—5 of Figure 3; and

Figure 6 is a diagrammatic sectional view of the package.

Although the apparatus forming the subject-matter of this invention is not limited to packaging any specific type of strand, nevertheless, it has been found particularly satisfactory when used to package glass or other inorganic or syn-

thetic organic strands or filaments. Strands of this type are usually manufactured in continuous lengths and are wound into a package as they are formed. Usually the speed of forming is limited by the speed at which the strand may be wound. The apparatus to be presently described enables a considerable length of strand to be packaged on a single holder and at high speed without interrupting production.

10 In the present embodiment of the invention the winding apparatus is disclosed in connection with means for forming glass filaments. This means may include a feeder 8 for molten glass having a plurality of feeding orifices from which streams of molten glass flow. The streams are attenuated in suitable manner as by a rotating spool 9 upon which the finished filaments are wound. Intermediate the feeder and the spool the filaments are collected by a guide 10 to form a strand 11. This apparatus may be similar to that disclosed in the Fisher Patent No. 2,224,149.

The strand 11 is wound around the spool 9 or any equivalent rotatable member in a manner to form a plurality of superposed rows of adjacent turns of the strand. As shown in Figure 6, the rows are centered with respect to one another axially of the spool and the rows progressively decrease in length from the inner row 12 to the outer row. Although the difference in length of succeeding rows may vary widely in accordance with the results desired, nevertheless, I have shown a package in Figure 6 wherein each succeeding row has the end turns spaced axially inwardly from the preceding row approximately the width of two strands. This affords a sufficient slope to the opposite ends 14 of the package to enable winding a strand on the spool or support 9 at very high speed without the danger of the strands sliding off one another or otherwise becoming snarled or tangled.

With the above in view reference will be made to Figures 1 and 2 wherein it will be noted that the strand is guided by an eye 15 supported at one side of and in proper relation to the spool 15 by the outer end of a traversing arm 17. The traversing arm 17 is pivotally supported on a fixed frame 18 by a pivot 19 which enables the eye 15 to swing through an arc lengthwise of the spool and to traverse the strand 11 along the spool. The opposite end portion 20 of the traversing arm is engaged by a carriage 21 which reciprocates along a path substantially parallel to the axis of rotation of the spool 9 and is operatively connected to the end portion 20 of the traversing arm 17 by an adjustable device 22

mounted on the carriage. The device 22 is movable step by step relative to the carriage and perpendicular to the path of travel of the carriage and slidably engages the end portion 20 of the traversing arm 17.

It follows from the brief description above that the length of the lever arm at the right of the pivot in Figure 2 or, in other words, the distance between the pivot 19 and the point of engagement of the device 22 with the end portion 20 of the traversing arm 17 may be varied. Variation of the effective length of this lever arm, of course, varies the length of the arc through which the eye 15 moves relative to the spool and enables the build-up of the strands on the spool to be controlled.

As will be more fully hereinafter explained, the device 22 is automatically adjusted at each cycle of traversing movement of the eye 15 by indexing means 24. In practice the effective length of the lever arm 20 is increased equal increments on successive traversing cycles of the eye 15. As a result, the extent of successive traversing movements of the eye 15 on the end of the traversing arm 17 is reduced from about the maximum travel at the time the first layer of strand is wound on the spool to about the minimum travel when the last layer is wound thereon. The amount of reduction of successive traversing movements is gauged by the required degree of slope of the end walls of the package and in the present case is selected to obtain the slope indicated in Figure 6.

Referring now more in detail to the apparatus briefly outlined above, the carriage 21 has laterally spaced side plates 28 secured together by end plates 29 and a bottom plate 30. Spaced aligned openings 31 extend through the side plates and the bottom plate adjacent the bottom edges of the carriage for receiving bushings 32. The bushings 32 respectively slidably receive laterally spaced rods 33 which extend substantially parallel to the axis of rotation of the rotatable spool 9 and are secured at opposite ends to a pair of fixed plates 34.

The slide or carriage 21 is reciprocated through a fixed distance by a cam 36 supported between the plates 34 by being fixed on a rotatable shaft 37 having the opposite ends respectively journaled in the plates and operatively connected to suitable driving mechanism indicated generally in Figure 1 by the reference character 38. The periphery of the cam has a continuous groove 39 for receiving a follower 40 projecting downwardly from and suitably secured to the slide 21. The configuration of the peripheral groove 39 is such that one complete revolution of the cam effects a movement of the slide 21 in opposite directions throughout the required distance and, due to the connection between the slide and traversing arm 17, moves the eye 15 on the outer end of the arm throughout one traversing cycle.

As stated above, the length of the traversing movement of the eye 15 depends on the length of the lever arm 20 and the latter is varied by adjusting the connecting device 22 relative to the pivot 19 for the traversing arm 17. The device 22 comprises a revoluble screw 41 supported between the side plates 28 of the carriage 21 by being journaled at opposite ends in the end plates 29. The construction is such as to enable rotation of the screw 41 relative to the slide 21 about an axis perpendicular to the path of travel of the slide 21. A nut 42 is threaded on the screw and is provided with a pivotally

mounted, upwardly extending projection 43 slotted as at 44 to slidably receive the end portion 20 of the traversing arm 17.

The nut 42 is of sufficient width to engage the side plates 28 on the slide 21 to be held from rotation with the screw 41. As a result, rotation of the screw in opposite directions respectively moves the nut 42 toward and away from the pivot 19. It is also pointed out at this point that the nut 42 is in the form of a half nut, being threaded only on the lower half. The threaded part of the nut is yieldably held in threaded engagement with the bottom side of the screw 41 by a plurality of springs 45 having the lower ends seated on the bottom plate 30 of the carriage and having the upper ends abutting a pressure plate 46. The pressure plate is slidably supported between the side plates 28 and engages the bottom side of the nut 42 to hold it in threaded engagement with the screw throughout the travel of the nut.

In the present instance, the screw 41 is rotated during successive traversing movements of the arm 17 to move the device 22 step by step in a direction away from the pivot 19 to successively increase the length of the effective lever arm 20 by equal increments and thereby gradually reduce successive traversing movements of the outer end of the arm 17. Rotation of the screw 41 in the direction necessary to obtain the above operation is accomplished by the indexing means 24. This means comprises a ratchet wheel 47 suitably secured to one end of the screw 41 and having circumferentially spaced teeth 48 for successively engaging the free end of a spring arm 49 having the other end fixed to a lug on the frame 18 of the machine by a screw 50.

The actuator spring 49 is so positioned with respect to the slide 21 that when the latter is moved in one direction by the cam 36, one tooth on the ratchet wheel 47 is engaged by the free end of the spring 49 so that continued movement of the slide in the same direction imparts a rotative movement to the screw 41. The extent of rotative movement of the screw 41 is predetermined by the spacing of the teeth on the ratchet wheel to obtain the adjustment of the lever arm 20 required to secure the selected decrease in the traversing movement of the outer end of the arm 17.

It will be noted from Figure 4 of the drawings that the angular spacing of the ratchet wheel 47 is such that when the ratchet is advanced one increment by engagement with the actuator 49, the next adjacent ratchet tooth is moved to a position for engagement with the actuator during the next succeeding cycle of the traversing movement of the slide 21. The ratchet is held against accidental rotation by means of a leaf spring 51 having one end secured to the slide 21 and having the free end yieldably engaging the side of the ratchet wheel opposite the side engaged by the actuator 49.

At the completion of a package the apparatus is set up for the next winding operation by manual return of the nut 42 to starting position. This is done by pressing the nut downwardly against the action of the springs 45 therebelow until the threaded lower half of the nut is disengaged from the threads on the screw. While being held in this disengaged relation, the nut is moved to starting position at opposite end of the carriage 21.

The present apparatus is a relatively simple automatic adjustable packaging mechanism for

strands, which enables effectively reducing the length of succeeding rows of the strands on the spool to impart a substantial slope to the opposite end walls of the package. This arrangement is highly advantageous, enabling a substantial length of strand to be packaged without discontinuing the production of the strand and without the danger of the strands becoming snarled or tangled upon high speed rotation of the package.

Modifications may be resorted to within the spirit and scope of the appended claims.

I claim:

1. Apparatus for packaging strands comprising a spool over which a strand is to be wound, means for traversing the strand along the spool including an arm having one end portion slidably engaging the strand and pivotally supported intermediate the ends to enable the said end portion to swing in opposite directions lengthwise of said spool, motion transmitting means having a uniform travel in opposite directions substantially parallel to the axis of rotation of the spool, a screw supported on the motion transmitting means for rotation about an axis extending substantially perpendicular to the axis of rotation of the spool, a nut releasably engaging said screw and slidably engaging the portion of the arm at the side of the pivotal support opposite the strand-engaging end of the arm, resilient means for holding said nut in operative engagement with said screw, and means responsive to movement of the motion transmitting means during each traversing cycle to impart a rotative movement to the screw in a direction to move the nut in a direction away from the pivotal support for the arm.

2. Winding apparatus comprising a rotatable spool over which a strand is to be wound, means for traversing a strand along the spool including a frame, an arm having one end portion guidingly engaging the strand and pivoted intermediate its ends to said frame to enable the said end portion to swing in opposite directions lengthwise of the spool, a slideway on said frame extending substantially parallel with the axis of rotation of the spool, a carriage on said slideway movable in opposite directions therealong, a sliding element supported on the carriage for movement toward and away from the pivotal support for the arm and slidably engaging the end portion of the arm at the side of the pivotal support opposite the strand-engaging end of the arm, and means for moving said element relative to the support for the arm during each traversing cycle of the strand-engaging end of the arm.

3. Winding apparatus comprising a rotatable spool over which a strand is to be wound, means for traversing the strand along the spool including a frame, an arm having one end portion slidably engaging the strand and pivoted intermediate its ends to said frame to enable the said end portion to swing in opposite directions lengthwise of the spool, a slideway on said frame extending substantially parallel with the axis of rotation of the spool, a carriage on said slideway movable in opposite directions therealong, a

sliding element supported on the carriage for movement crosswise of said slideway toward and away from the pivotal support for the arm and slidably engaging the end portion of the arm at the side of the pivotal support opposite the strand-engaging end of the arm, and means operable during successive traversing cycles of the strand-engaging end of the arm to move the element step by step in a direction away from the pivot and thereby reduce the length of successive traversing movements of the strand-engaging end of the arm, including a screw rotatably supported on said carriage, a threaded connection between said screw and the sliding element on the carriage, and means for periodically rotating said screw.

4. Winding apparatus comprising a rotatable spool onto which a strand is to be wound, means for traversing a strand along the spool including a frame, an arm having one end portion guidingly engaging the strand and pivoted intermediate its ends to said frame to enable the said end portion to swing in opposite directions lengthwise of said member, a slideway on said frame extending substantially parallel with the axis of rotation of the spool, a carriage on said slideway movable in opposite directions therealong, an adjustably sliding element supported on the carriage for movement crosswise of said slideway toward and away from the pivotal support for the arm, a stud rotatably mounted on said sliding element and slidably engaging the portion of the arm at the side of the pivot for the arm opposite the strand-engaging end of said arm, and means responsive to movement of the carriage for successively moving the sliding element equal increments in a direction away from the pivot for the arm during succeeding traversing cycles of the arm.

5. Winding apparatus comprising a spool over which a strand is to be wound, a frame, means for traversing the strand along the spool including an arm having one end portion slidably engaging the strand and pivotally supported intermediate its ends to enable the said end portion to swing in opposite directions lengthwise of said spool, a cam mounted for rotation on said frame, a pair of bars secured in said frame and extending in substantial parallelism with the axis of rotation of said spool, a carriage slidably supported on said bars for sliding movement in opposite directions therealong, a projection on said carriage in engagement with said cam to cause reciprocation of the carriage upon rotation of said cam, a screw supported on the carriage for rotation about an axis extending substantially perpendicular to the axis of rotation of the spool, a nut on said screw slidably engaging the portion of the arm at the side of the said pivot for said arm opposite the strand-engaging end of the arm, and means responsive to movement of the carriage during each traversing cycle to impart a rotative movement to the screw in a direction to move the nut in a direction away from the pivot for the arm.

ED FLETCHER.
